AX

Fred C. Greene, Freeport, Maine

Application October 25, 1940, Serial No. 362,715

5 Claims. (Cl. 145—2)

This invention relates generally to axes and more particularly to safety axes of the type which comprises movable parts adapted to shield the cutting edge when the ax is not to be used.

The invention is particularly applicable to small hand axes or hatchets of the type intended to be carried by hunters or surveyors or other persons having occasion to use a light instrument for cutting small pieces of wood, such as firewood or stakes or twigs or other things of similar character. This type of ax is usually carried in some form of holster or is strapped to the person in such a manner that it is desirable or even necessary that the cutting edge be shielded to prevent accidental injury to the user. Such axes should be of such a form that their construction is simple and practical, whereby they may be folded or otherwise adjusted to a condition in which they may be used and also to a condition in which the edge is shielded for purposes of safety. At the same time their construction must be such that they do not cause injury by collapsing during use or wear out because of complicated or flimsy construction.

Accordingly, the principal object of this invention is to provide a novel safety ax of simple and sturdy construction.

A further object of the invention is to provide a light ax, the bit of which may be shielded during periods of non-use.

Still another object of this invention is to provide a safety ax comprising a minimum number of parts and involving a minimum cost of manufacture.

Further objects and advantages of the invention will be apparent from consideration of the following specification and accompanying drawing, wherein:

Fig. 1 is an elevation of the ax in partially operated condition showing certain parts in section;

Fig. 2 is an elevation with parts broken away to show cross sections of the ax in its open position;

Fig. 3 is a fragmentary view partly in section of the ax in its closed or shielded condition;

Fig. 4 is an end view of the shield shown in Fig. 1;

Fig. 5 is an end view of the ax head shown in Fig. 1;

Fig. 6 is an end view of the ax illustrated in Fig. 2; and

Fig. 7 is an end view of the ax illustrated in Fig. 3.

Fig. 8 is a cross-section view taken on line 8—8 of Fig. 2.

Fig. 9 is a cross-section view taken on line 9—9 of Fig. 2.

A safety ax constructed in accordance with the invention as illustrated in Fig. 1 comprises an enclosing handle portion 1, an ax head shield 2 integral with handle 1, a haft 4 and an ax head 5 integral with the haft and comprising a butt portion 3 together with a cutting edge 6. The haft 4 is swivelled to handle 1 by means of a ball and socket joint comprising a socket 7 which is integral with handle 1 and ball 8 integral with haft 4. Handle 1 is provided with grip 20 which may be rubber or any other suitable material.

Fig. 2, and Fig. 8 and Fig. 9 illustrate the ax after it has been adjusted for use as a cutting tool. The haft 4 has been moved from the position shown in Fig. 1 in such a manner that it is enclosed in slot 11 of the handle 1 and the butt 3 of the ax head 5 is enclosed by the shield 2, the surfaces 9 and 10 of the shield and the ax head respectively having been brought into juxtaposition whereby the component parts of the instrument are in firm relation to one another.

15 The handle 1 and the haft 4 are maintained in the operating position by means of the pin 18 as illustrated in Fig. 2 and Fig. 8. A latch 12, pivotally fastened by rivet 13, is slotted to fit in a notch at the end of pin 18 in such a manner that a press or spring fit is obtained whereby the pin cannot slip from the position shown.

20 After the ax has been used and it is desired to adjust it to the safety condition, pin 18 is removed and the head is removed from the shield to the position illustrated in Fig. 1 and rotated 180° until the cutting edge 6 faces the opening at the bottom of shield 2 whereupon the head may be inserted within the shield to the position illustrated in Figs. 3 and 7. The pin 18 is then reinserted and fastened in position by latch 12 whereby the cutting edge 6 is shielded by shield 2 and all danger of injury is removed.

25 From the above description it is evident that during periods of use all component parts of the instrument are neatly fitted together in such a manner that the device may be used in any desired manner either as a cutting instrument or as a hammer without danger of collapse and consequent personal injury. It is further evident that the shield is fully operative to prevent personal injury during periods of non-use and the instrument is still compact and neat in appearance.

30 Further modifications of the invention will be evident to those skilled in the art and conse-

quently it is my desire that the invention shall be limited only by the appended claims and as required by the prior art.

I claim:

1. An ax comprising a head with a cutting edge, a haft attached to the head, a casing for said head having an opening, a slotted handle attached to the casing, a portion of said handle having a contour suitable to render it usable as a grip, a socket at one end of said handle and a ball at one end of said haft fitted within said socket whereby the ax head may be rotated and inserted in the opening in said casing in a shielded position or a cutting position and means for securing the haft within the handle.

2. An ax comprising a head with a cutting edge, a haft attached to the head, a slotted casing for said head and haft, a portion of said casing having a contour suitable to render it usable as a handle and a socket at one end of said casing and a ball at one end of said haft fitted within said socket whereby the ax head may be rotated and inserted within the casing in a shielded position or a cutting position.

3. An ax comprising a head with a cutting

edge, a haft attached to the head, a channeled casing for said head and haft and a socket at one end of said casing and a ball at one end of said haft fitted within said socket whereby the

5 ax head may be inserted and withdrawn from the casing and rotated to a shielded position or a cutting position.

4. An ax comprising a head with a cutting edge, a haft attached to the head, a slotted casing for said head and haft, a portion of said casing having a contour suitable to render it usable as a handle and a swivel connection between the haft and casing whereby the ax head may be inserted and withdrawn from the casing and rotated from a shielded position to a cutting position.

10 5. An ax comprising a head with a cutting edge, a haft attached to the head, a casing having an opening for admitting said head and a slotted handle attached to the casing and a swivel connection between the handle and haft whereby the head and haft may be rotated and inserted within the casing and handle respectively in a shielded position or a cutting position.

20 25 FRED C. GREENE.
